[57] ABSTRACT

[21] Appl. No.: 328,277

The discard removing device is for removing the billet discard and extrusion disc from the extrusion axis after the billet discard has been cut off from the remainder of the extrusion. The device has a pivotal mounting frame which pivots towards and away from the extrusion axis and gripping jaws on the mounting frame for gripping the discard; the gripping jaws are mounted on the mounting frame by means of a parallel link which enables the gripping jaws to move up and down, which parallel link can be tilted to enable the gripping jaws to be tilted away from the extrusion axis.

DISCARD REMOVING DEVICE FOR AN EXTRUSION PRESS

BACKGROUND OF THE INVENTION

The invention relates to a discard removing device on a horizontal metal extrusion and tube presse, particularly for flat sections of aluminium.

It used to be common practice to extrude aluminium billets of circular cross-section into sectional stock. Later, the same presses were also used to extrude billets of nearly rectangular cross-section in addition to those of circular cross-section because substantially broader extrusion sections, more particularly flat sections, can be produced from billets of rectangular cross-section rather than from those of circular cross-section. The cross-sectional area of the rectangular cross-sectional billets was kept approximately the same as that of the circular cross-section billets so that the specific pressure for extruding the billets also remained the same. The conversion from circular to flat or rectangular cross-section billets was mainly done in the heavier extrusion presses.

To this end it is important to ensure as far as possible automatic and trouble-free operation of the auxiliary devices for such presses, these devices being adapted to load into the press the billet and the extrusion disc disposed behind the billet and to remove the extrusion discard comprising the billet discard (also known as the butt) and the extrusion disc from the press after the billet is extruded from the billet container of the press and through the die. When the extrusion discard is removed it is also important to ensure that the extrusion discard is transferred reliably and in a precisely defined position to an extrusion discard cutting device which is disposed outside the press.

For extrusion, a heated billet is placed in the billet container of the extrusion press, an extrusion disc is positioned behind the billet to prevent the rear end of the billet sticking to the ram and a ram forces the material of the billet through the die, which can be of any suitable form. At the end of extrusion, the rear end of the billet and the extrusion disc are still behind the die and the rear end of the billet is integral with the extruded tube or section which extends out in front of the die and has its rear end in the die. Normal practice is for the container to be withdrawn, pulling the rear end of the billet and extrusion disc out of the container, and for the rear end of the billet and the extrusion disc to be cut off, usually by shearing, immediately behind the die by a cropping blade which moves generally vertically downwards. Once the extrusion discard has been cut off, it is usually desirable to cut it; in some cases, the extrusion disc may have adhered to the billet discard and be of a material different from the billet, in which case the disc should be cut off from the discard; in other cases, it is necessary to cut up the billet discard for easy handling and re-melting.

German Auslegeschrift No. 1,141,606 discloses an extrusion discard removing device in which a collecting dish is mounted on a pivoting arm which is disposed outside the press. The said collecting dish may be lowered on the pivoting arm in such a way that it is able to pivot laterally into the press below the extrusion discard and is placed below the said discard after being raised. When the billet discard is cropped off by a shear from the extruded strand, the collecting dish is thrust

vertically downward by the extrusion discard. The collecting dish with the extrusion discard may pivot out of the middle of the press after the shears return into an upper position. The collecting dish shown in that Specification is suitable only for circular sections. Grippers cannot be attached.

U.S. Pat. No. 3,129,818 discloses an extrusion discard removing device comprising a first lever which can be hydraulically pivoted into the press at right angles to the extrusion axis. A further lever is pivoted to the upper end of the first lever and is approximately horizontally positioned and retained by a hydraulic cylinder when the main lever has been pivoted inwards, the free end of the second lever supporting a fixedly mounted collecting dish or catch-pan for the extrusion discard, the said dish also having spring-loaded grippers for gripping the extrusion discard. This extrusion discard removing device may also be lowered by the second arm during the inward pivoting motion so that the grippers may pivot past the exposed extrusion discard and the collecting dish is disposed directly under the extrusion discard when the second arm pivots upwardly. After the extrusion discard is clamped between the spring-loaded grippers, the collecting dish is deflected downwardly in a circular arc about the pivoting point of the second arm on the first (main) lever when the cropping operation is performed. Since flat billets are thrust downwardly when in the horizontal position while being cropped by the shears but the collecting dish with the grippers is downwardly deflected along a circular arc, it follows that the removing device would thrust a flat billet out of the grippers when moving downwardly. This results in an unreliable and undefinable position of the extrusion discard.

There has also been proposed a discard removing device which is suitable for removing round and flat extrusion discard billets, the device being adapted to deflect vertically downwardly during the cropping operation. However, this device is very complex. This is because the collecting dish travels vertically below the press frame or below the foundation cover after the extrusion discard is cropped off until the extrusion discard may be conveyed horizontally outwardly and upwards through the foundation cover into the zone of the extrusion discard cutting device. The extrusion discard stack rests freely on the support so that extrusion discs of larger diameter may readily topple over. The conveying distances are long and the guides required in the zone below the press can become very dirty and there is a risk of damage from falling extrusion discs.

SUMMARY OF THE INVENTION

The present invention provides a discard removing device for a horizontal extrusion press, the device comprising:

mounting means for sideways movement towards and away from the extrusion axis of the press; gripping means for gripping the extrusion discard, for movement into and out of the zone of the extrusion axis as the mounting means is moved towards and away from the extrusion axis; and a parallel link and tilting means mounting the gripping means on the mounting means such that when the mounting means have been moved towards the extrusion axis, the gripping means can be moved up and down or tilted towards and away from the extrusion axis about an axis parallel to the extrusion

axis, either simultaneously or in separate movements.

The invention extends to a horizontal extrusion press having a generally vertically downwardly movable cropping blade for cropping off the discard and a discard removing device in accordance with the invention for removing the discard from the extrusion axis.

The invention can provide an extrusion discard removing device, more particularly for flat billets of aluminium, which can be of simple construction and maintenance and can be moved into and out of the extrusion axis in a simple manner, which is also capable of reliably gripping the extrusion discard despite its varying dimensions resulting from the cropping operation.

The device of the invention is capable of removing the extrusion discard out of the press between the extrusion axis and the press frame by moving the mounting means away from the extrusion axis and supplying the discard in a precisely defined position to an extrusion discard cutting device, more particularly if the gripping means is pressure fluid actuated to improve retention of the extrusion discard in the gripping means and the gripping means yields vertically downwardly during the cropping operation due to the parallel link means and is tilted away from the extrusion axis after a vertical (upwards) return motion or is tilted away from the extrusion axis during the vertical return motion.

Preferably, the parallel link and tilting means comprises an upper, generally horizontal lever pivoted to said mounting means, the lever having its free, front end portion pivoted to the gripping means, and a generally vertical lever pivoted to the mounting means on the same pivot axis as that between the generally horizontal lever and the mounting means (which pivot axis can be formed by a pivot pin fixed to the mounting means), the generally vertical lever having its free lower end portion movably connected to (e.g., pivoted to) one end portion of a second generally horizontal lever whose other end is pivoted to the gripping means.

To enable the parallel link and tilting means to yield under the shear pressure when the extrusion discard is cropped, the up and down movement of the gripping means may be actuatable by a double-acting pressure fluid piston-cylinder unit having two cylinder chambers of identical effective cross-sectional area, which chambers are interconnected by an e.g., adjustable restrictor but which interconnection can be closed.

Since the extrusion discard, which comprises the billet discard and the extrusion disc, has a specific length and cropping may cause the billet discard to become broader than the extrusion disc, the gripping means may comprise two spaced pairs of gripping jaws disposed one behind the other, which pairs of jaws may be actuatable by a single actuating unit by way of a lever compensating system so that the gripping action of each pair of jaws can be either the same or different; the lever compensating system preferably comprises a two-armed compensating lever to the centre portion of which the single actuating unit is connected while the two end portions are connected (either directly or through intermediate members such as levers) by way of ball joints to the respective pairs of gripping jaws. This arrangement can ensure that both pairs of gripping jaws always act with substantially the same force and that they are able to grip dimensions of different magnitude.

Each of the pairs of gripping jaws may comprise two rocker levers which are pivoted to a carrying member such as a collecting dish which is provided with the gripping jaws, which rocker levers have respective toothed lower horizontal free ends, for instance in the form of segments, which mesh with each other and upper generally vertical free ends which carry gripping heads. Force need be applied to only one of the rocker levers because of the, e.g., segmented tooth coupling between the two rocker levers. If, as is preferred, the gripping heads are pivoted to the respective jaws, the pivoted gripping heads can ensure that the full width of their, e.g., flat sides always bears flush on the stepped extrusion discs or on the billet discard which is usually slightly deformed by the cropping operation so that the discard and extrusion disc are reliably held.

The mounting means is preferably a frame to be disposed outside the press and pivotal about a stationary pivot axis which is parallel to the extrusion axis, i.e., pivotable for movement in a plane perpendicular to the extrusion axis, the gripping jaws being mounted on the free upper end of the pivotal frame. In general, the mounting means is preferably arranged for pivoting through an angle of substantially 90° between its two limiting positions to enable an extrusion discard of flat section to be set down in a vertical position in the cutting device outside the press. Preferably, the mounting means can move parallel to the extrusion axis; this is important if one extrusion program involves cutting the extrusion discard with shears and a standard die and another extrusion program operates with a bridge or chamber die, in which the extrusion discard is torn off axially from the section and in its entirety is longer and must be taken up in a different axial position by the gripping means.

BRIEF DESCRIPTION OF THE DRAWINGS

One embodiment of the invention is now particularly described, by way of example, with reference to the accompanying drawings, in which:

FIG. 1 is a cross-section, looking in the extrusion direction, through part of a horizontal metal extrusion press, showing a discard removing device in accordance with the invention;

FIG. 2 is a section through the discard removing device, along the line II-II in FIG. 1;

FIG. 3 corresponds generally to FIG. 1, but the full lines show the discard removing device with its frame pivoted inwards and with the collecting dish tilted down, while the broken lines show the discard ejection device with its frame pivoted outwards;

FIG. 4 likewise corresponds generally to FIG. 1, but shows the discard removing device with its frame pivoted inwards, with the collecting dish horizontal and with an extrusion discard gripped by the gripping means at the end of a cropping operation with the cropping shear in its lowest position;

FIG. 5 shows a detail of FIG. 1, on an enlarged scale;

FIG. 6 is a section through the force transmission lever of the gripping means, along the line VI-VI in FIG. 5;

FIG. 7 is a plan view of the gripping means in the position shown in FIG. 8, on an enlarged scale;

FIG. 8 is a view corresponding generally to that of FIG. 5, but showing an extrusion discard gripped by the gripping means; and

FIG. 9 is a view in the direction of the arrow A in FIG. 5, showing the lever compensating system of the gripping device on an enlarged scale.

DESCRIPTION OF A PREFERRED EMBODIMENT

A base frame 4 is disposed adjacent to a horizontal metal extrusion press for extruding sections and tubes. Of the press, only part of the press frame 1, the tie rods or columns 2 joining the work holder and cylinder member of the press and a vertically acting cropping device 3 are shown. Mounting means in the form of a pivoting frame 5, comprising two side walls (see FIG. 2), is non-rotationally but axially slidably disposed on a horizontal shaft 6. The shaft 6 is pivotably supported in bearings 7 disposed in the base frame 4. The pivoting frame 5 is pivoted into or out of the press by means of a lever 8, non-rotationally mounted on the shaft 6, and a hydraulic cylinder 9 which is pivoted to the base frame 4. An abutment 10 on the pivoting frame 5 limits the inward pivotal movement of the pivoting frame 5 by abutting the press frame 1.

A two-armed generally horizontal lever 12 is pivoted on a bolt 11 mounted on that end of the pivoting frame 5 which is uppermost and closest to the press. The leading free end of the lever 12 is pivoted to an upper joint 13 of a collecting dish 14 (which forms part of gripping means) while the rear free end of the lever 12 is pivoted by means of a bolt 16 to a hydraulic piston-cylinder unit 17 (which may be referred to as a ram) which is in turn pivoted on the pivoting frame 5 by means of bolts 17'.

A further, generally vertical, two-armed lever 19 is also pivotable about the bolt 11 mounted on the pivoting frame 5 while the upper free end of the lever 19 is pivoted at 18 to a further hydraulic piston-cylinder unit 21 which is pivoted to the pivoting frame 5 at a pivot 20, the lower free end being joined to a simple radius rod 22 by means of a bolt 23. The other end of the radius rod 22 is pivoted to the collecting dish 14 at a lower joint 24 by means of a bolt 25.

The levers 12 and 19 and the radius rod 22 form a combined parallel link and tilting means.

When the piston-cylinder unit 21 is not operated and the piston-cylinder unit 17 is operated, the collecting dish 14 is displaced parallel either upwardly or downwardly.

When the piston-cylinder unit 17 is not operated, (i.e., when the upper joint 13 of the collecting dish 14 is fixed in space), and the piston-cylinder unit 21 is operated, the collecting dish 14 will be downwardly tilted by means of the radius rod 22 which is retracted to the right in the drawing (see FIG. 3). Combined operation of both piston-cylinder units 17 and 21 causes the parallel and tilting motions to be superimposed upon each other.

The two cylinder chambers of the piston-cylinder unit 17 are of identical area and are provided with a double-acting piston and communicate with each other through an adjustable restrictor 28 disposed between ducts 26 and 27 (see FIG. 1). This permits parallel and slow lowering of the collecting dish 14 under the thrust applied by the cropping device 3. Communication between the ducts 26 and 27 and therefore through the restrictor 28 may be opened and closed by means of a valve 15. The cylinder spaces of the piston-cylinder

unit 17 are supplied with hydraulic fluid by way of the respective ducts 26 and a direction valve 59.

The collecting dish 14 is of L-shape, the upper joint 13 at which the two-armed lever 12 is pivoted to the collecting dish 14 provides a vertical part, while the lower joint 24 at which the radius rod 22 is pivoted to the collecting dish and an extrusion discard support 29 provides the horizontal part. The extrusion discard support 29 is constructed so that it is able to retain an extrusion discard from a round billet 48 as well as an extrusion discard from a flat billet 49. A further hydraulic piston-cylinder device 30 is hinged by means of trunnions 31 on the vertical part of the collecting dish 14. The end of the piston rod 32 of the piston-cylinder device 30 (see FIG. 9) is provided with a clevis 33 which pivots a two-armed compensating lever 35 by means of a bolt 34 (see FIG. 6). The two ends of the compensating lever 35 are connected by ball joints 36 and 37 to two-armed vertical levers 38, 39 which are also hinged at their pivot point 40 to the vertical part of the collecting dish 14.

FIGS. 1, 2 and 3 show the levers 38, 39 disposed one behind the others. Links 41 are hinged at the lower free end of both levers 38 and 39, the other end of the links being pivotably joined to grippers 42. The grippers 42 comprise pairs of grips each with two jaws or rocker levers 42a and 42b each of which is supported so as to pivot about bolts 43 and 44, respectively on the horizontal part of the collecting dish 14. At their inward facing ends, the rocker levers 42a and 42b have toothed segments 45 by means of which they are coupled so that the force transmitted to the rocker levers 42a by the links 41 is transmitted via the toothed segments 45 to the other rocker levers 42b and both rocker levers 42a, 42b have common movement although oppositely orientated pivoting motions about the respective bolts 43 and 44.

The upper free ends of the rocker levers 42a and 42b are provided with gripping heads 46 which are pivotably supported by means of trunnions 47 in the respective rocker levers 42a and 42b. The full width of the flat side of the gripping heads 46 bears upon the extrusion discard, either of a round billet 48 or of a flat billet 49, the gripping heads 46 swivelling by means of their trunnions 47 so that they bear fully on the side surfaces of the extrusion discard if such surfaces are not parallel.

A hydraulic cylinder 51 (see FIG. 2) whose piston rod is coupled by means of a link bolt 50 to the lever 8, provides axial displacement of the pivoting frame 5 on the shaft 6.

When pivoted outwards through an angle of 90°, a supporting roller 53 mounted on the pivoting frame 5 bears on a rail 54 which is mounted on the base frame 4.

FIG. 8 shows a round extrusion discard cropped off by the shears 3 and comprising an extrusion disc 55 and a billet discard 56, slightly ovaly deformed by the cropping operation; the extrusion discard is located in the collecting dish 14 and is gripped by pairs of grips 42 and 42' which are disposed one behind the other.

In another advantageous construction, the two-armed vertical lever 19 is replaced by a single lever whose upper end is hinged to the bolt 11 which is fixed in the pivoting frame 5 and whose lower end is coupled by means of bolts 23 to the radius rod 22, the hydraulic

piston-cylinder unit 21 being pivoted to the pivoting frame 5 so as to act on the bolt 23.

The operation of the extrusion discard removing device is as follows:

The pivoting frame 5, ready for inward pivoting, is disposed outside the press. The upper cylinder chamber of the piston-cylinder unit 17 is pressurised so that the lever 12 is retained at a slight angle, being upwardly inclined to the left. The piston-cylinder unit 21 has its right-hand cylinder chamber pressurised so that the piston rod moves the lever 19 anti-clockwise. This causes the radius rod 22 to pull the lower joint 24 of the collecting dish 14 to the right. Accordingly, the collecting dish 14 tilts downwardly while pivoting anti-clockwise about the upper joint 13.

The right-hand cylinder chamber of the piston-cylinder unit 30 is pressurised so that the pairs of grips 42 open. The piston rod 32 thrusts the upper free end of the two-armed levers 38, 39 to the left so that the lower ends of the levers 38, 39 pull the rocker levers 42a and 42a' to the right. The left-hand rocker levers 42b and 42b' move to the left due to the coupling which is provided by the toothed segments 45.

The hydraulic cylinder 9 is then pressurised so that the pivoting frame 5 pivots to the left about its pivot shaft 6 until its stop abutment 10 abuts the press frame 1 (FIG. 3). The collecting dish 14 in its downward tilted state is pivoted into the press, passing between the upper right-hand column 2 of the press and the upper edge of a press frame 1 and between the container 57 and a press die 58 (see FIG. 2).

Pressurising the other chamber of the piston-cylinder unit 21 causes the collecting dish 14 to be pivoted clockwise into a horizontal position directly under the extrusion discard which comprises the billet discard 56 and the extrusion disc 55. The left-hand gripping heads 46 will pivot past the outer left-hand edge of the billet discard into the position indicated in FIG. 1. During this operation the collecting dish 29 comes into contact with the lower edge of the extrusion discard.

After the upward tilting motion, the pairs of rocker levers 42a, 42a' and 42b, 42b' will close due to appropriate pressurising of the piston-cylinder unit 30. One pair of grips will then grip the extrusion disc 55 while the other pair grips the billet discard 56 (see FIG. 7).

The billet discard 56 is cropped off by means of the shears 3 from the extruded strand (not shown) after the extrusion ram (not shown) and the billet container 57 are retracted. The cropping operation sometimes deforms the billet discard 56 to such an extent that its original circular shape becomes oval (see FIG. 8). However, the compensating lever 35 enables the pairs of grips 42 and 42' to adapt themselves automatically to the different widths of the billet discard 56 and the extrusion disc 55. The gripping heads 46 also adjust themselves to an inclined position if the billet discard merges with a taper into the extrusion disc.

Prior to the cropping operation, the two cylinder chambers of the piston-cylinder unit 17 are connected through the adjustable restrictor 28 by means of the valve 15 so that the collecting dish 14 with the billet discard 56 and the extrusion disc 55 is thrust parallel to the downward direction against a corresponding resistance by the restrictor 28 during the cropping operation. The parallel downward motion of the collecting dish 14 is accompanied by a slight lateral deflection rel-

ative to the vertical and corresponding to the circular arc of the upper joint 13 of the lever 12 about the bolt 11. This deflection is of no significance for circular sections and more particularly for flat sections because the clamped extrusion discard is able to slide horizontally while being cropped by the shear knife 3.

After the shears 3 retract and after communication between the chambers of the piston-cylinder unit 17 is closed, the piston-cylinder unit 17 is pressurised by the valve 59 so that the lever 12 moves clockwise and the collecting dish is once again raised in parallel. After reaching the starting position (see FIG. 1), but with the billet discard clamped or gripped, the collecting dish 14 is tilted down by pressurising the right-hand chamber of the piston-cylinder unit 21. This enables the billet discard and the gripping heads 46 to pass by the upper right-hand column 2 when the pivoting frame 5 is pivoted out of the press.

When the pivoting frame 5 has been pivoted outwards through 90°, the piston-cylinder unit 21 is pressurised so that the collecting dish 14 once again tilts upwards. The billet discard 56, for example 1, the flat section 49, will then be positioned vertically on a cutting device, not shown, for cutting off the extrusion disc from the billet discard (shown in broken lines in FIG. 1).

The pivoting frame 5 may be displaced parallel to the extrusion axis by means of the hydraulic cylinder 51, depending on the extrusion programme and depending on the method by which the billet is cut.

I claim:

1. A discard removing device for a horizontal extrusion press having a press frame, the device comprising:

mounting means pivotally movable about a pivot axis parallel to the extrusion axis and in a plane generally perpendicular to said extrusion axis, said mounting means having an upper free end portion;

pressure fluid actuatable means for pivoting said mounting means about said pivot axis;

gripping means for gripping the extrusion discard, for pivoting out of and into said extrusion axis between said extrusion discard and said press frame;

pressure fluid actuatable means for actuating said gripping means;

combined parallel link and tilting means mounting said gripping means on said upper free end portion of said pivotal mounting means, whereby said gripping means can be moved up and down and tilted towards and away from said extrusion axis about an axis parallel to said extrusion axis, either simultaneously or in separate movements;

and pressure fluid actuatable means for moving said gripping means up and down and tilting said gripping means.

2. A discard removing device for a horizontal extrusion press having a press frame, the device comprising:

mounting means pivotally movable about a pivot axis parallel to the extrusion axis and in a plane generally perpendicular to said extrusion axis, said mounting means having an upper free end portion;

pressure fluid actuatable means for pivoting said mounting means about said pivot axis;

gripping means for gripping the extrusion discard for pivoting out of and into said extrusion axis between said extrusion discard and said press frame; pressure fluid actuatable means for actuating said gripping means;

combined parallel link and tilting means mounting said gripping means on said upper free end portion of said pivotal mounting means, whereby said gripping means can be moved up and down and tilted towards and away from said extrusion axis about an axis parallel to said extrusion axis, either simultaneously or in separate movements; and pressure fluid actuatable means for moving said gripping means up and down and tilting said gripping means;

said combined parallel link and tilting means comprising an upper, generally horizontal lever pivoted to said mounting means, said lever having a free front end portion pivoted to said gripping means, a generally vertical lever pivoted to said mounting means on the same pivot axis as that between said generally horizontal lever and said mounting means, and a second generally horizontal lever having a first end portion and a second end portion pivoted to said gripping means, said generally vertical lever having a free lower end portion movably connected to said first end portion of said second generally horizontal lever.

3. A discard removing device as claimed in claim 2, wherein said first generally horizontal lever is a two-armed lever having a front arm and a rear arm, said rear arm having a rear end portion, and wherein said pressure fluid actuatable means for moving said gripping means up and down and tilting said gripping means comprises a pressure fluid piston-cylinder unit which is pivotally connected to said rear end portion of said rear arm and pivotally connected to said mounting means.

4. A discard removing device as claimed in claim 3, wherein said generally vertical lever is a two-armed lever having an upper arm and a lower arm, said upper arm having an upper end portion, and wherein said pressure fluid actuatable means for moving said gripping means up and down and tilting said gripping means comprises a pressure fluid piston-cylinder unit which is pivotally connected to said upper end portion of said upper arm and is also pivotally connected to said mounting means.

5. A discard removing device for a horizontal extrusion press having a press frame, the device comprising:

mounting means pivotally movable about a pivot axis parallel to the extrusion axis and in a plane generally perpendicular to said extrusion axis, said mounting means having an upper free end portion;

pressure fluid actuatable means for pivoting said mounting means about said pivot axis; gripping means for gripping the extrusion discard for pivoting out of and into said extrusion axis between said extrusion discard and said press frame; pressure fluid actuatable means for actuating said gripping means; combined parallel link and tilting means mounting said gripping means on said upper free end portion of said pivotal mounting means, whereby said gripping means can be moved up and down and tilted

towards and away from said extrusion axis about an axis parallel to said extrusion axis, either simultaneously or in separate movements;

and pressure fluid actuatable means for moving said gripping means up and down and tilting said gripping means;

said pressure fluid actuatable means for moving said gripping means up and down and tilting said gripping means comprising a double-acting pressure fluid piston-cylinder unit for moving said gripping means up and down, said double-acting pressure fluid piston-cylinder unit comprising two cylinder chambers of identical effective cross-sectional area, closable fluid interconnection means interconnecting said chambers and a restrictor in said interconnecting means.

6. A discard removing device for a horizontal extrusion press having a press frame, the device comprising:

mounting means pivotally movable about a pivot axis parallel to the extrusion axis and in a plane generally perpendicular to said extrusion axis, said mounting means having an upper free end portion;

pressure fluid actuatable means for pivoting said mounting means about said pivot axis;

gripping means for gripping the extrusion discard for pivoting out of and into said extrusion axis between said extrusion discard and said press frame;

pressure fluid actuatable means for actuating said gripping means;

combined parallel link and tilting means mounting said gripping means on said upper free end portion of said pivotal mounting means, whereby said gripping means can be moved up and down and tilted towards and away from said extrusion axis about an axis parallel to said extrusion axis, either simultaneously or in separate movements;

and pressure fluid actuatable means for moving said gripping means up and down and tilting said gripping means;

said gripping means comprising a collecting dish and gripping jaws pivoted to said collecting dish.

7. A discard removing device for a horizontal extrusion press having a press frame, the device comprising:

mounting means pivotally movable about a pivot axis parallel to the extrusion axis and in a plane generally perpendicular to said extrusion axis, said mounting means having an upper free end portion;

pressure fluid actuatable means for pivoting said mounting means about said pivot axis;

gripping means for gripping the extrusion discard for pivoting out of and into said extrusion axis between said extrusion discard and said press frame;

pressure fluid actuatable means for actuating said gripping means;

combined parallel link and tilting means mounting said gripping means on said upper free end portion of said pivotal mounting means, whereby said gripping means can be moved up and down and tilted towards and away from said extrusion axis about an axis parallel to said extrusion axis, either simultaneously or in separate movements;

11

and pressure fluid actuatable means for moving said gripping means up and down and tilting said gripping means;

said gripping means comprising two spaced pairs of gripping jaws disposed one behind the other, and wherein said pressure fluid actuatable means for actuating said gripping means comprises a single actuating unit and a lever compensating system connected to each pair of gripping jaws, whereby the gripping action of each pair of jaws can be either the same or different.

8. A discard removing device as claimed in claim 7, wherein said lever compensating system comprises a two-armed compensating lever having a center portion and two end portions, said single actuating unit being connected to said center portion, and force transmitting means connecting said two end portions to said pairs of gripping jaws, said force transmitting means comprising ball joints.

9. A discard removing device as claimed in claim 7, wherein said gripping means comprises a carrying member and wherein each said pair of said gripping jaws comprises two rocker levers pivoted to said carrying member, said rocker levers having respective toothed lower generally horizontal free ends which mesh with each other and upper generally vertical free

12

ends, gripping heads being mounted on said upper free ends of said rocker levers.

10. A discard removing device as claimed in claim 8, wherein said gripping means comprises a carrying member and wherein each said pair of said gripping jaws comprises two rocker levers pivoted to said carrying member, said rocker levers having respective toothed lower generally horizontal free ends which mesh with each other and upper generally vertical free ends, gripping heads being mounted on said upper free ends of said rocker levers.

11. A discard removing device as claimed in claim 9, wherein said gripping heads are pivoted to said upper free ends of said rocker levers.

12. A discard removing device as claimed in claim 1, wherein said mounting means has two limiting positions of movement and is pivotable through an angle of substantially 90° between said two limiting positions.

13. A discard removing device as claimed in claim 1, wherein said mounting means is movable parallel to said extrusion axis.

14. A discard removing device as claimed in claim 2, wherein said mounting means is movable parallel to said extrusion axis.
